(57) **CLAIM**

The ornamental design for a projector-equipped digital camera, as shown and described.

DESCRIPTION

FIG. 1 is a perspective view of a projector-equipped digital camera showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view taken along line 8-8 in FIG. 2, wherein the internal structure is omitted;

FIG. 9 is a cross-sectional view taken along line 9-9 in FIG. 2, wherein the internal structure is omitted;

FIG. 10 is a perspective view of a projector-equipped digital camera according to a second embodiment of the present design;

FIG. 11 is a front elevational view thereof;

FIG. 12 is a rear elevational view thereof;

FIG. 13 is a top plan view thereof;

FIG. 14 is a bottom plan view thereof;

FIG. 15 is a right side elevational view thereof;

FIG. 16 is a left side elevational view thereof; and,

FIG. 17 is a cross-sectional view taken along line 17-17 in FIG. 11, wherein the internal structure is omitted.

The broken lines are shown for illustrative purposes only and form no part of the claimed design. The dashed-dotted lines denote the boundary of the claim and form no part of the claimed design.
